UNITED STATES PATENT OFFICE.

HARRIS B. HOLT, OF DORMONT BOROUGH, PENNSYLVANIA, ASSIGNOR TO ROSEDALE FOUNDRY & MACHINE COMPANY, OF PITTSBURGH, PENNSYLVANIA, A CORPORATION OF PENNSYLVANIA.

CHAIN CONVEYER.

1,122,204.

Specification of Letters Patent. Patented Dec. 22, 1914.

Application filed March 2, 1914. Serial No. 821,980.

To all whom it may concern:

Be it known that I, HARRIS B. HOLT, residing at Dormont Borough, in the county of Allegheny and State of Pennsylvania, a citizen of the United States, have invented or discovered certain new and useful Improvements in Chain Conveyers, of which improvement the following is a specification.

10 My invention relates to continuous chain conveyers, and has particularly to do with conveyers known as chain grates for furnace stokers.

15 The object thereof is to provide links and connecting rods of such a character that the links may be laterally applied to or removed from the rods, rather than slipping the rods through the links, the attachment to or removal of one end of a link from a rod, 20 when the other end of the link is rotatably mounted on an adjacent rod, being effected solely by the simultaneous rotation of the first named rod on its axis and the link upon the second named rod.

25 In the accompanying sheet of drawings, which forms part of my specification, I have illustrated the preferred embodiment of my invention.

30 Figure 1 is a plan view of a portion of a chain conveyer particularly adapted to be used as a part of a furnace stoker; Fig. 2 a combination side and longitudinal sectional view of the chain illustrated in Fig. 1; and Fig. 3 a view, to enlarged scale, of a link and a pair of adjacent connecting rods, the link being shown in an intermediate position of being removed from or attached to the right hand connecting rod.

35 In the several figures like numerals are used to designate like parts.

40 In the practice of my invention all or a portion of the conveyer may be constructed of links and rods embodying my improvements. In Fig. 3 there is shown a pair of 45 adjacent parallel connecting rods 1 and 2 and a single grate link. For purposes of description and definition the rod 1 may be called a holding rod and the rod 2 a locking rod, although it will be readily understood from the further description of the 50 rods that the holding rod may have the same

general structural characteristics as the locking rod. The link, which has a coal sustaining face 3, is provided at its opposite ends with seats 4 and 5 for the rods 1 and 55 2, respectively, the seat 4 preferably having any suitable open slot leading to it, so that the link may be applied laterally to the rod 1. The seat 5 also has a rod-receiving slot leading to it, but of a configuration essentially restricted with relation to the relative positions of the rods 1 and 2 and the form of the rod 2. As shown herein the outer side of the slot leading to the seat 5 is formed by a tongue 6, the end of which 60 faces or points toward the seat 4. The rod 1 is preferably cylindrical throughout, while the rod 2 is provided with preferably a single continuous groove or recess 7 longitudinally of its axis.

65 The rod 2 is rotatable, and, when the rod 1 is in the link seat 4 and the rod 2 turned with its recess 7 facing the tongue 6, the tip of the tongue rests in the recess, as shown in Fig. 3. However, when the link 70 is thus applied to the rod 1, the unrecessed surface of the rod 2, when the several successive points thereof are turned to their most remote position from the center of the seat 4 or rod 1, are at a greater distance 75 80 from the center of such seat than is the tip of the tongue 6. By such an arrangement it will be seen that, when the link and rods are in the positions indicated in Fig. 3, a turning of the rod 2 in a right handed direction will cause the link to be fed upon such rod, the link simultaneously rotating on the rod 1. After the link is thus attached to the rod 2 it will readily be seen that it 85 cannot be removed without rotating such 90 rod in the opposite or left hand direction.

As shown herein, the link may be symmetrical, the slot leading to the seat 4 having a tongue 6^a on the outer side, and of the same shape as the tongue 6. When thus 95 constructed, the slots leading to the seats 4 and 5 incline toward the general center line of the link, and the distance between the tips of the tongue 6 and 6^a is less than the distance between parallel planes touching the outer faces of adjacent rods in whatever relative positions such rods may be 100

turned. In other words the distance A in Fig. 2 is less than the distance B, the rod 2^a being turned to such position that a plane touching the outer edges of the recess 7 is 5 nearest to a parallel plane touching the outer side of the rod 1^a.

In constructing the chain grate, as illustrated in Figs. 1 and 2, the cylindrical holding rods 1 are arranged alternately with 10 the grooved locking rods 2, and the links forming each continuous longitudinal line are staggered with relation to the links of the next adjacent lines. In order to keep the locking rods from rotating while the 15 conveyer is in use, the outside links 8 are provided with closed rod seats, one of which seats in each link has a detent 9 adapted to extend into the groove or recess 7 of a rod 2. These outside links may be slipped over 20 the ends of the rods and held thereon by means of cotter pins 10. By locking the rods 2 in the positions indicated in Figs. 1 and 2, the links, unless broken, cannot be removed accidentally unless the rod should be 25 twisted through an arc of approximately 270°, which, under the conditions of service, is practically impossible. In case any of the links should break, and this is not an unusual occurrence in chain grates for stokers, 30 it may be replaced by removing the end locking links 8 from the locking rod to which such link was attached, turning the rod to the position indicated in Fig. 3, and applying the link in the manner there shown.

35 I claim as my invention:

1. In a continuous chain conveyer including transversely arranged rods and rod-connecting links, the combination of a holding rod, a locking rod parallel thereto and 40 provided with a longitudinally disposed recess with oppositely disposed walls, and a link provided at its ends with rod seats and extending between and rotatable upon each of said rods, the seat for the locking rod 45 having an open slot leading thereto, the outer face of the slot terminating in a tongue facing the holding rod seat; the end of the tongue fitting into the recess of the locking rod when such recess faces the tongue; and 50 the outer surface of the unrecessed portions of the locking rod, as the successive points thereof are turned to their most remote positions from the holding rod seat, being of a greater distance from the center of such 55 seat than the tip of the tongue, whereby the link may be attached to or removed from the locking rod solely by the simultaneous rotation of the link upon the holding rod and the locking rod upon its own axis.

60 2. In a continuous chain conveyer including transversely arranged rods and rod-connecting links, the combination of a holding rod having a substantially unbroken cylindrical surface, a cylindrical locking rod 65 parallel thereto and provided with a lon-

gitudinally disposed recess, and a link provided at its ends with rod seats and extending between and rotatable upon each of said rods; the seat for the locking rod having an open slot leading thereto, the outer face of the slot terminating in a tongue facing the holding rod seat; the points of the surface of locking rod, except the recess therein, being, when such points are turned to their most remote positions from the center of the 75 holding rod seat, at a greater distance from said seat center than the tip of the tongue, whereby the link may be attached to or removed from the locking rod solely by the simultaneous rotation of the link upon the 80 holding rod and the locking rod upon its own axis.

3. In a continuous chain conveyer including transversely arranged rods and rod-connecting links, the combination of a holding 85 rod, a locking rod parallel thereto rotatable and provided with a longitudinally disposed recess, a link provided at its ends with rod seats and extending between and rotatable upon each of said rods, the seats having rod 90 receiving slots leading to them, the outer margins of such slots being formed by tongues having their tips facing each other and the center line of the link, the distance between the tips of the tongues being less 95 than the minimum distance between parallel planes touching the outer faces of the rods, as the locking rod rotates.

4. In a continuous chain grate for a furnace stoker including transversely arranged 100 rods and rod-connecting links, the combination of parallel alternately arranged holding and locking rods, each holding rod having a substantially unbroken cylindrical surface and each locking rod being rotatable 105 and provided with a continuous longitudinal groove; a plurality of intermediate longitudinal lines of links, each link extending between and rotatably mounted upon an adjacent pair of rods, the links forming each 110 line being staggered with relation to the links of the next adjacent lines; each of said links being provided at its ends with rod seats having rod receiving slots leading to them, the outer faces of such slots being 115 formed by tongues having their tips facing each other and the center line of the link, the distance between the tips of the tongues of each link being less than the minimum distance between parallel planes touching 120 the outer faces of the rods to which such link is attached as the locking rod rotates; and a line of locking links at each edge of the grate, each of said locking links engaging a locking rod and holding it immovable 125 with relation to an adjacent holding rod.

5. In a chain grate including transversely arranged rods and rod-connecting links, the combination of two rods extending in parallelism, and a connecting link; the two rods 130

being substantially cylindrical, one of them provided with a recess having oppositely disposed walls and being rotatable; the said link being provided with rod seats; one of said rod seats being accessible to said recess-provided rod through a slot whose outer lip overhangs in the direction of the other rod seat and in the simultaneous rotation

of said recess-provided rod on its own axis and said link on said other rod. 10

In testimony whereof I have hereunto set my hand.

HARRIS B. HOLT.
